UNITED STATES PATENT OFFICE.

JOHN SCOTT-TAGGART, OF BOLTON, ENGLAND.

VACUUM TUBE FOR RADIO APPARATUS.

Application filed October 26, 1920, Serial No. 419,703, and in Great Britain November 29, 1919.

The present invention relates to means of supporting electrodes in vacuum tubes and the like, especially tubes of the two electrode or three electrode type used in wireless communication.

The two electrode vacuum tube, chiefly used as a rectifier of high voltage alternating currents, usually consists of a metal filament surrounded by a substantially cylindrical anode of sheet metal.

The anode has been previously supported by means of supporting wires sealed at one end to a glass stem. Such construction, however, is unsuitable for large vacuum tubes owing to the liability of the glass to crack.

My invention enables the anode to be very firmly supported by special means by the use of which the endangering of the glass work is avoided.

Referring now to the drawings, Fig. 1 is a view of a vacuum tube funnel with the fastening wires; Fig. 2 shows the funnel supporting the anode; Fig. 3 shows the funnel supporting the filament; Fig. 4 shows a tube with the funnel support embodied therein and Fig. 5 is a view showing screw threaded fasteners on the funnel.

The invention consists broadly in fixing electrode or like elements in vacuum tubes and the like by securing the supporting members of the said elements by means of wires or rivets or the like having a portion thereof embedded at suitable places in the insulating material of the tubes such as the wall of a funnel or member extending into the tube, the remainder of such wires or rivets being arranged to extend into the vacuum space of the tube in such a manner as to facilitate their attachment to the supporting members of the said elements.

In order to secure the electrodes in position in the tubes the free ends of the fixing wires may be bent over or around the supporting members of the elements, or passed through holes formed therein, and then twisted together.

Various methods may be adopted for preventing the supporting members slipping through the fastening wires, for example these wires may be passed through holes drilled in the supporting members, or the supporting members may be narrowed or tapered at the points where they are to be secured by the wires.

The fastening wires are preferably in the form of staples or U-shaped members of

which the bend of the U or a portion thereof is embedded in the insulating material of the tube preferably the funnel portion thereof.

The U-shaped holding wires may have their bent portions longitudinally or transversely arranged with respect to the funnel. In the former case two holes may be drilled in each supporting member in positions for receiving the respective members of each U-shaped fastener, so that the ends of a fastener project through each pair of holes where they can be twisted or tied together. Two or more of such U-shaped fasteners may be used for each supporting member; these may both be arranged longitudinally or transversely, or when two are used, one may be arranged longitudinally and the other transversely.

The electrode supporting wires are preferably of channel or other suitable cross-section to give them mechanical strength and rigidity.

When the fastening takes the form of a rivet the free end thereof is passed through a hole in a supporting member of the element and then bent over or otherwise distorted, or when split rivets are used the ends are bent in opposite directions. In a modification of the fastening the free ends of the wires are screw-threaded and adapted to pass through holes in the supporting members of the said elements, the said ends being provided with nuts.

Various applications of the invention are illustrated in the accompanying drawings. Fig. 1 being a view of a funnel for a vacuum tube showing three pairs of U-shaped fastening wires preferably of nickel-iron alloy, platinum-coated metal, platinum, or other metal having a co-efficient of expansion comparable to that of glass or whatever the substance to which the supporting members are secured having their U-shaped ends embedded just below the surface thereof at regular intervals so that the free ends of each fastener can be twisted together after being bent over or around one of three supporting members extending from an electrode as shown in Fig. 2.

In these drawings a^1 to a^6 are the fastening wires, b the funnel of the vacuum tube, c^1 to c^6 the supporting members of the anode d as in Figs. 2 and 4 or the filament element e in Fig. 3, or the grid element f in Fig. 4, these supporting members may be secured

to the anode by any suitable means as by riveting or clamping them to each end of the anode. g is the leading-in terminal to the anode, h^1 and h^2 the current terminals of the filament, and i the terminal of the grid element.

In the method of supporting the filament e in Fig. 3 the ends of the filament are held by metal strips extending from the pinched portion of the funnel b and the bend of the filament supported by the bent end of supporting member c^1 secured to the funnel b by fastening wires a^1 and a^2 .

The lower ends of the filament e are secured to those shown in Fig. 4 to a funnel b^1 in the lower end of the tube, the upper portion of the bend of the filament being supported by one end of a spiral member m , the other end of the spiral member being supported by a projection formed at the end of the upper funnel b .

The grid element is carried by supporting members c^1 , c^2 and c^3 fastened by wires a^1 to a^6 to the lower funnel b^1 . The leading terminal to this grid is shown at i . In a modification of this construction both the grid and the anode are mounted on the same stem as the filament the external connections being kept well apart.

Fig. 4 illustrates a modified form of a three electrode tube k wherein the anode $\mathcal{A}$ is carried by a supporter c^1 fastened to the funnel b by fastening wires a^1 and a^2 . In this tube the grid f is carried by a supporter c^2 fastened to the funnel b by fastening wires a^3 and a^4 .

The filament e is secured at its lower end to an extension of the funnel b and at its upper end to a spiral supporting wire m to the top of the tube.

The terminals h^1 , h^2 , g and i are provided with caps h^3 , h^4 , g' and i' .

A full-wave rectifier carrying my invention into effect might be constructed by mounting a cylindrical anode on the same stem as the filament, a convenient external connection to the anode being made. Another anode mounted as described above could be inserted from the other end of the bulb, the filament being large enough to pass through the axis of each anode.

In order to strengthen the aforementioned constructions, it may be desirable to pass a binding wire around the tubular stem preferably at the points where the support members are tied to the stem. In some cases the electrodes may be supported by securing the supporting members in the special manner described to the inside wall of the vacuum tube preferably close to the neck where the diameter of the tube is small.

Vacuum tubes may be made with one electrode mounted in accordance with this invention, and another electrode mounted by tying the supporting wires to a stem.

Various combinations of these methods may be devised and also used if desired, in conjunction with already well known methods of construction.

While electrodes of cylindrical form have been described it is possible to support electrodes of other shapes in the same substantial manner.

Large cylinder anodes may be mounted by using a triangular support to give greater rigidity. In order to provide such a triangular support the supporting member c^1 , c^2 and c^3 Fig. 2, instead of ending at the left-hand extremity may be bent over at this point to form an acute angle and the end of the member affixed to the anode at the same point as its other extremity, thus completing a triangular structure of greater strength than the single member.

It is possible to arrange a vacuum tube having a plurality of electrodes each supported from the same stem or funnel in the manner herein described.

What I claim and desire to secure by Letters Patent is:—

1. An electric translator for translating electric current into light, heat and radiations, comprising a closed glass vessel containing an electrode and a glass funnel, means whereby current can be supplied to the electrode, an electrode support, and fastening devices of which one end is embedded in the glass funnel, the other end of the fastening device holding the electrode support against the glass funnel.

2. The method of fixing electrodes having supporting members, in closed glass vessels provided with means whereby current can be supplied to the electrodes, according to which method the supporting members of the electrodes are fastened to the material of the vessel by twisting together wires bent over the supporting members of the electrodes and of which portions are embedded in the material of the vessel.

3. An electric translator for translating electric current into light, heat and radiations, comprising a closed glass vessel containing an electrode and an inwardly extending glass funnel, means whereby current can be supplied to the electrode, an electrode supporting member, and fastening wires, the fastening wires having one end embedded in the funnel while their free ends are bent over towards each other from opposite sides of the electrode supporting member and twisted together.

4. An electric translator for transmitting electric current into light, heat and radiations, comprising a closed glass vessel containing an electrode, means whereby current can be supplied to the electrode, an electrode supporting member, and fastening wires, the fastening wires having one end embedded in the material of the vessel while

their free ends are bent over towards each other from opposite sides of the electrode supporting member and twisted together.

5. An electric translator for translating electric current into light, heat and radiations, comprising a closed glass vessel containing an inwardly extending glass funnel, a cylindrical electrode, means whereby current can be supplied to the electrode, an electrode supporting member and fastening wires, the fastening wires having one end embedded in the funnel while their free ends are bent over towards each other from opposite sides of the cylindrical electrode supporting member and twisted together.

6. An electron discharge tube having a glass funnel extending therein, an electrode supporting spring, a cylindrical electrode, a plurality of electrode supporting members, electric terminals, an inverted V-shaped filament and fastening wires, one of the supporting members of the cylindrical electrode being electrically connected to one of the electric terminals and the V-shaped filament extended into the central space of the cylindrical electrode and its bent end supported by the spring from the funnel and connected at its ends to the current supplying terminals, the fastening wires having portions embedded in the funnel and free end portions bent over and secured to the electrode supporting members.

7. An electron discharge tube having a glass funnel extending therein, an electrode supporting spring, a plurality of electrodes, a plurality of electrode supporting members, electric terminals, and fastening wires, one of the electrodes being cylindrical and a supporting member thereof electrically connected to one of the electric terminals, another of the electrodes being a filament electrically connected to two electric terminals and extending into the central space of the cylindrical electrode and supported by the supporting spring from the upper portion of the glass vessel and the fastening wires having portions embedded in the glass funnel and free end portions bent over and secured to the electrode supporting members.

50 8. An electric translator for translating electric current into light, heat and radiations, comprising a closed glass vessel containing an electrode, means whereby current can be supplied to the electrode, and electrode support, and metal fastening devices containing nickel and iron and of which one

portion is embedded in the glass of the closed vessel, and one end of the electrode supports being affixed to the electrode while the other is held in position against the material of the vessel by the fastening device.

60 9. An electric translator for translating electric currents into light, heat and radiations, comprising a closed glass vessel containing an electrode, and an inwardly extending glass funnel, means whereby current can be supplied to the electrodes, an electrode supporting member, and fastening wires of a metal containing nickel and iron, the fastening wires having one portion embedded in the funnel while their free ends are fixed to the supporting member of the electrode.

65 10. An electric translator for translating electric current into light, heat and radiations, comprising a closed glass vessel containing an electrode and an inwardly extending glass funnel, means whereby current can be supplied to the electrode, an electrode supporting member, and fastening wires, the fastening wires being in the form of staples of which the bends are embedded in the funnel while their free ends are bent over towards each other from opposite sides of the electrode supporting member and 70 twisted together.

75 11. An electric translator for translating electric current into light, heat and radiations, comprising a closed glass vessel containing an electrode and a glass funnel, means whereby current can be supplied to the electrode, a plurality of electrode supports and fastening devices of which one end is embedded in the glass funnel, the other end of the fastening device holding 80 the electrode supports against the glass funnel.

85 12. An electric translator for translating electric current into light, heat and radiations, comprising a closed glass vessel containing an inwardly extending glass funnel, a cylindrical electrode, means whereby current can be supplied to the electrode, a plurality of electrode supporting members, and fastening wires, the fastening wires having 90 one end embedded in the funnel while their free ends are bent over towards each other from opposite sides of the cylindrical electrode supporting members and twisted together.

100 In witness whereof I affix my signature.
JOHN SCOTT-TAGGART.
